**COMBINED TAPE MEASURE, ANNOTATION PAD,
AND STYLUS THEREFOR**Michel Quenot, Besancon, France, assignor to Manu-
facture Quenot Mabo, Besancon, France

Filed Dec. 3, 1971, Ser. No. 204,781

Claims priority, application France June 7, 1971

Term of patent 14 years

Int. Cl. D10—04

U.S. Cl. D52—1 R

FIG. 1

FIG. 2

FIG. 3

FIG. 4

FIG. 1 is a rear perspective view of a combined tape measure, annotation pad, and stylus therefor with the annotation pad in a partially inserted position, showing my new design;

FIG. 2 is a rear perspective view thereof with the annotation pad in a fully inserted position;

FIG. 3 is a front perspective view thereof; and

FIG. 4 is a rear elevational view thereof.

I claim:

The ornamental design of a combined tape measure, annotation pad, and stylus therefor, substantially as shown and described.
